(57) CLAIM

The ornamental design for a "large inverted tray," as shown and described.

DESCRIPTION

FIG. 1 is a perspective view of a large inverted tray from the front, above and right showing our new design;

FIG. 2 is a front elevational view thereof, the rear elevation being a mirror image thereof;

FIG. 3 is a top plan view thereof;

FIG. 4 is a bottom plan view thereof;

FIG. 5 is a right end view thereof, the left end view being a mirror image thereof; and,

FIG. 6 is a perspective view thereof from below.
